INSULATING CONNECTOR FOR WIRES

Mike Varga, New York, N. Y.

Application May 1, 1941, Serial No. 391,227

4 Claims. (Cl. 174—87)

This invention relates to new and useful improvements in an insulating connector for wires.

More particularly, the invention purposes the construction of a connector as mentioned, capable of tightly connecting wires together in a simple way.

More specifically, the invention proposes to characterize the connector by a tubular housing having a closed end and adapted to receive groups of wires into its open end, and a simple novel arrangement for holding the inner ends of these wires connected together.

More specifically, the invention contemplates providing a metallic sheet turned around the end portions of the wires and acting in a certain way in conjunction with portions on the tubular housing for forming the desired connection.

Still further it is proposed to form one of the wires at its inner end with a loop engageable with a complementary longitudinally extending groove formed on the inside of the tubular housing in a manner to prevent the wires from turning relative to the tubular housing.

Another object of the invention is the construction of a device as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of an insulating connector with wires constructed in accordance with this invention.

Fig. 2 is a vertical sectional view of Fig. 1.

Fig. 3 is a partial sectional view taken on the line 3—3 of Fig. 2.

Fig. 4 is a horizontal sectional view taken on the line 4—4 of Fig. 3.

Fig. 5 is a perspective view of the metallic sheet used in the connector.

Fig. 6 is a view similar to Fig. 2 but illustrating a modification of the invention.

Fig. 7 is a vertical sectional view taken on the line 7—7 of Fig. 6.

Fig. 8 is a perspective view of the inner ends of the group wires.

Fig. 9 is a perspective view similar to Fig. 8, but illustrating a group of wires made of three wires.

The insulating connector for wires, in accord-

ance with this invention, includes a tubular housing 10 having a closed end 11 and an open end 12. The housing 10 is also provided with an internal longitudinally extending groove 13 extended inwards from its open end 12. The housing 10 also has an external bead 10^a by which it may be conveniently gripped. A group of wires 14, 15 have one of their ends twisted together forming a coil 16. More specifically, the wire 14 forms the core of the coil 16 while the wire 15 is wound around this core portion. The wires 14 and 15 have insulating covering material 14^a and 15^a, respectively, along their length except at the twisted end portion. The wire 14 has its free end formed into a loop portion 17.

When the engaged ends of the wires 14 and 15 are inserted into the tubular housing the loop 17 will have its top (see Fig. 2) disposed with the groove 13 to prevent the wires from turning relative to the tubular housing 10.

A metallic sheet 18 is turned around the twisted ends, that is, the coil 16 of the wires 14 and 15. The metallic sheet 18 is formed from a piece of sheet metal bent substantially into tubular shape. A clamping member 20 is mounted on the housing 10 and abuts against the metallic sheet 18 for holding said sheet and the coil 16 of the wires 14 and 15 in position. More specifically, this holding member 20 comprises a screw of insulation material mounted through one wall of the housing 10.

With the parts as illustrated in Fig. 2 the wires 14 and 15 are electrically connected together and securely held within the casing 10.

If desired, the wires 14 and 15 may be removed by first loosening the screw 20 and then pulling out on the wires. The metallic sheet 18 may then be slightly opened to permit its being slipped off the coil 16.

In Figs. 6 and 7 a modification of the invention is illustrated which is similar to that previously described except that a metallic sheet is not engaged about the coil 16. In this form of the invention the wires are inserted into the tubular housing 10 and the holding screw 20 is rotated inwards to cause its inner end to bear directly against the coil 16 to hold the wires in position within the tubular housing 10.

In Fig. 8 a perspective view of the inner ends of the wires 14 and 15 is illustrated to show the manner in which the inner end of the wire 15 is wound around the inner end of the wire 14 to form the coil 16.

In Fig. 9 a perspective view of a group of wires formed of three separate wires is shown. In

this form of the invention wires 15 and 15' are wound around the inner end of a wire 14 to form a coil 16.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. An insulating connector for wires having a tubular housing with a closed end and a group of wires enclosed within a metallic sheath inserted into said housing through its open end, a clamping member on one side of said housing and engageable against said sheath for holding said sheath and wires against outward movement relative to said housing, and means holding said wires against rotation relative to said housing for assisting said clamping member in securely locking said sheath and wires within said housing.

2. An insulating connector for wires having a tubular housing with a closed end and a group of wires enclosed within a metallic sheath inserted into said housing through its open end, a clamping member on one side of said housing and engageable against said sheath for holding said sheath and wires against outward movement relative to said housing, and means holding said wires against rotation relative to said housing for assisting said clamping member in securely locking said sheath and wires within said housing, comprising a loop formed on the inner end of one of said wires and having its top portion dis-

posed within a longitudinal groove formed in said housing.

3. An insulating connector for wires having a tubular housing with a closed end and a group of wires enclosed within a metallic sheath inserted into said housing through its open end, a clamping member on one side of said housing and engageable against said sheath for holding said sheath and wires against outward movement relative to said housing, and means holding said wires against rotation relative to said housing for assisting said clamping member in securely locking said sheath and wires within said housing, comprising a loop formed on the inner end of one of said wires and having its top portion disposed within a longitudinal groove formed in said housing, said groove being extended inwards from the open end of said housing enabling said loop to be properly engaged within said groove from the time said wires are inserted into said housing.

4. An insulating connector for wires having a tubular housing with a closed end and a group of wires enclosed within a metallic sheath inserted into said housing through its open end, a clamping member on one side of said housing and engageable against said sheath for holding said sheath and wires against outward movement relative to said housing, and means holding said wires against rotation relative to said housing for assisting said clamping member in securely locking said sheath and wires within said housing, comprising a loop formed on the inner end of one of said wires and having its top portion disposed within a longitudinal groove formed in said housing, said wire having said loop being extended beyond the inner end of said sheath and other wire.

MIKE VARGA.
